UNITED STATES PATENT OFFICE.

JOSEPH JOSEPH GLATT, OF ST. MARYS, PENNSYLVANIA.

LIFTING JACK.

Application filed December 9, 1922. Serial No. 605,919.

To all whom it may concern:

Be it known that I, JOSEPH J. GLATT, a citizen of the United States, residing at St. Marys, in the county of Elk and State of Pennsylvania, have invented new and useful Improvements in Lifting Jacks, of which the following is a specification.

My invention relates to a lifting jack which is especially adapted to be used in raising the journal boxes of railway cars, in order to effect the removal or insertion of the brasses.

The general object of the invention is to provide a simple, strong, durable, efficient and inexpensive device which may be quickly and easily manipulated for the purpose mentioned.

A more specific object of the invention is to provide a device of this kind, including a lever, which is adapted to be intermediately fulcrumed on the upper rim of a car wheel, to one end of which power may be applied to raise the other end thereof and thereby raise the journal box.

Another object of the invention is to provide a jack adapted to be attached to the wheel in such a manner that the applied forces may be so distributed, that they exert a direct pull, and there is no lateral strain on the wheel, nor any tendency to dislodge the mechanism therefrom.

With the above and other objects in view, which will be made apparent as the description proceeds, the invention consists in the construction, arrangement and combination of parts which will be more particularly described in connection with the accompanying drawings forming a part of this specification.

In the drawings:

Fig. 1 is a side elevation of a car wheel and journal box showing my invention applied thereto.

Fig. 2 is a view similar to Fig. 1, but showing the parts in a different position.

Fig. 3 is a rear elevation of the parts shown in Fig. 2.

Fig. 4 is a view similar to Fig. 3, but showing a modified form.

Fig. 5 is a side elevation showing a further modification.

Fig. 6 is a view similar to Fig. 5, but showing the parts in a different position.

Fig. 7 is a rear elevation showing a still further modification.

Fig. 8 is a detail view showing a modified form of toggle connection.

Fig. 9 is a side elevation showing another modification of the invention.

Fig. 10 is a view similar to Fig. 9, but showing the parts in a different position.

Fig. 11 is a rear elevation of the parts shown in Fig. 9.

I have shown my invention as used in connection with a car wheel 1, mounted on axle 2, which is journaled in a box 3, the latter being provided with brasses 4 and 5, on which the frame 6 of the truck is supported.

The invention includes a lever 7 having a transversely-extending flange 8 which is adapted to rest upon the upper surface of the car wheel, and is provided with one or more grooves 9, any one of which is adapted to fit the wheel flange. A rod 10 is suitably connected with one end 11 of the lever, and

is secured at its lower end around the axle 2 in any suitable manner, as shown at 12. The rod is preferably provided with a turn-buckle 13 for the purpose of adjustment. The other end 14 of the lever has a pivotal connection with a pair of toggle links 15 and 16, the lower ends of which are pivotally connected to blocks 17 and 18, which are provided with internal right and left hand threads, respectively. Another pair of toggle links 19 and 20 are pivotally connected at their upper ends to blocks 17 and 18 and at their lower ends are pivotally connected to the upper bar 21 of a frame within which the journal box 3 is adapted to be received.

The side members 22 of the frame are preferably pivoted to the upper bar 21, and at their lower ends carry a bar 23 which may be secured in any suitable manner, preferably by an adjustable connection, as shown at 24.

In the operation of the jack, the same is fitted to the car wheel with the lever 7 resting upon the top surface thereof, and the rod 10 suitably adjusted and connected with the axle 2. The journal box receiving frame

may be adjusted so that the bar 23 engages underneath the outer portion of the journal box, or it may be engaged with the journal box inside of the truss frame 6, as indicated by dotted lines in Fig. 3.

The blocks 17 and 18 of the toggle receive a rod 25 which is oppositely threaded to correspond with the right and left hand threads of the blocks, and said rod may be operated by suitable ratchet levers 26 and

27.

The blocks 17 and 18 of the toggle receive a rod 25 which is oppositely threaded to correspond with the right and left hand threads of the blocks, and said rod may be operated by suitable ratchet levers 26 and

26^a. Thus, by rotating the rod 25, the toggle may be spread from the position shown in Fig. 1 to that shown in Fig. 2, thereby raising the journal box and permitting the brasses to be withdrawn. If desired, an extension 27, as indicated in dotted lines in Fig. 1, may be provided for attachment to the end of the rod 25, which extension may be suitably journaled and supported upon a tripod 28 or the like which may rest upon a railroad tie 29, and be connected at its upper end to the car body, as indicated at 30. The levers 26 and 26^a are interchangeable and may be applied to either end of the rod 25 or to the end of the extension 27.

The size and shape of the lever 7 may be varied in accordance with the type of truck on which the same is used, or according to the individual preference of the mechanics 20 who use the same. As shown in Fig. 4, the lever 7^a is made comparatively short so that the outer end thereof terminates inside of the truck frame 6, and the toggles and frame 22 are arranged in substantially a vertical 25 plane between the truck frame and the car wheel.

In the form shown in Figs. 5 and 6, the screw-threaded rod 25 is arranged immediately above the journal box, the toggle 30 links 15^a and 16^a being comparatively long, and the lower pair of toggle links 19^a and 20^a extending on each side of the journal box and being directly connected with the lifting bar 23^a. In this form, the bar 23^a 35 is preferably provided with teeth 31 by means of which it may be quickly connected to the links 19^a and 20^a by the adjustable pins 31^a.

In Fig. 7, I have shown another modification of the invention as applied to a Fox truck. In this form a fulcrum block 32 is provided, which rests upon the upper surface of the car wheel and has a rib 33 which acts as a pivot for the lever 34, the latter 40 being preferably provided with a plurality of grooves 35 for adjustably receiving the rib 33. A suitable frame 36 is connected to the outer end of the lever 34 and extends underneath the journal box 3^a. The inner 45 end of the lever is connected with toggle links 37 and 38 similar to the toggle links heretofore described, the links being, in this case, connected with the axial inside of the wheel. The lever 34, as well as the levers 7 and 7^a, may be of any suitable shape and 50 size. As shown in Fig. 7, the inner end is bent downwardly as indicated at 39, so as to give ample room for the operation thereof.

In Fig. 8, I have shown a modified form 60 of toggle connection, in which the lever 7^b, similar in other respects to lever 7, is provided at its outer end with an integral hook 40, which is inserted through a hole in the 65 toggle block 41. The toggle block has a

pivotal connection with the upper links 42 of the toggle.

In the modification illustrated in Figs. 9, 10 and 11, a fulcrum block or shoe 43 is fitted to the car wheel and provided with a groove 44 to fit over the flange thereof. The fulcrum block has on its upper surface a rib 45 which fits into one of the grooves 46 to provide a fulcrum for the lever 47 which is similar to the lever 7^b, and is provided at its outer end with an integral hook 48. A toggle block 49 is supported by the hook 48, and pivotally supports the two pairs of links 50 and 51 which extend outwardly on either side of the journal box and have their lower ends bent downwardly. Between each pair of links 50 and 51, near their lower ends, is mounted a roller 52 having a peripheral groove 53 in which is supported an angle iron 54 which is T-shaped in cross section. The lever and links are initially adjusted so that the angle iron 54 will engage the under side of the journal box 55 in the position shown in Fig. 9. Between the lower ends of the links 50 and 51, beneath the rollers 52 are pivotally supported blocks 56 having openings therethrough which are provided with right and left hand threads, respectively, to receive the oppositely threaded ends of a rod 57 which is similar to the rod 25 previously described. Ratchet levers may be applied to the opposite ends of the rod 57, as shown at 58, to adjust the links 50 and 51, outwardly or inwardly to raise or lower the journal box in the same manner as described in connection with those forms of the invention above described.

It will be apparent to those skilled in the art that the invention may be quickly and easily applied for the purpose described, and since the same does not rest upon the ground, there is no time lost in providing a suitable support therefor. The device is quickly applied to the upper surface of the wheel, and the forces at each end of the lever are balanced so that there is no strain on the wheel flange and no tendency for the same to be dislodged therefrom, no matter how much the flange may be worn. It is also apparent that the toggle links actuated by the screw-threaded rod permit the easy application of the force necessary to raise the journal box.

From the foregoing description, the advantages of my construction and the method of operation of the same will be readily understood, and while I have described the principle of the invention, in connection with those forms which I now consider to be the preferred embodiments thereof, it will be understood that these forms are merely illustrative, and that various other modifications may be devised within the scope of what is claimed, without departing from the principles of the invention.

What is claimed is:—

1. A jack of the class described comprising a lever adapted to be fulcrumed intermediate its ends on the rim of a car wheel, means for anchoring one end of the lever to the axle, means for connecting the other end of the lever to the journal box, and means for decreasing the effective length of said connecting means to raise the journal box. 65
2. A jack of the class described comprising a lever adapted to be fulcrumed intermediate its ends on the rim of a car wheel, means for anchoring one end of the lever to the axle, vertically adjustable means adapted to extend beneath the journal box and having a pivotal connection with the other end of the lever, and means for gradually decreasing the distance between the lever and said vertically adjustable means to raise the journal box. 70
3. A jack of the class described comprising a lever adapted to be fulcrumed intermediate its ends on the rim of a car wheel, means connecting one end of the lever to the axle, means for connecting the other end of the lever to the journal box, and means for gradually decreasing the effective length of one of said connecting means. 75
4. A jack of the class described comprising a lever adapted to be fulcrumed intermediate its ends on the rim of a car wheel, means connecting one end of the lever to the axle, means for connecting the other end of the lever to the journal box, one of the connecting means including toggles, and means for spreading said toggles to decrease the effective length of said connecting means. 80
5. A jack of the class described comprising a lever adapted to be fulcrumed intermediate its ends on the rim of a car wheel, means for anchoring one end of the lever, means for connecting the other end of the lever to the journal box, including toggles, and means for spreading said toggles to decrease the effective length of said connecting means. 85
6. A jack of the class described comprising a lever adapted to be fulcrumed intermediate its ends on the rim of a car wheel, means for anchoring one end of the lever, toggles connected to the other end of the lever, a bar having a vertically adjustable connection with the lower ends of the toggles and adapted to extend underneath the journal box, and means for spreading said toggles to decrease the distance between the bar and the lever. 90
7. A jack of the class described comprising toggles, means for pivotally supporting the upper ends of said toggles at a fixed point above the journal box, a bar underneath the journal box and connected to the lower ends of the toggles, and means for spreading the toggles to raise the journal box. 95
8. A jack of the class described comprising toggles, a lever adapted to be pivotally supported intermediate its length on the rim of a car wheel, said lever having a link connection at one end with the axle and having its other end pivotally connected with the upper ends of said toggles at a fixed point above the journal box, a bar adapted to extend underneath the journal box and connected to the lower ends of the toggles, and means for spreading the toggles to raise the journal box. 100
9. A jack of the class described comprising a pair of toggle links, means for pivotally supporting the upper ends of said links at a fixed point above the journal box, a frame adapted to extend underneath the journal box, another pair of toggle links pivotally connected at their lower ends to the frame, a pair of blocks to which the free ends of both pairs of toggle links are pivotally secured, a rod having right and left hand threaded connections with the respective blocks, and means for rotating said rod to spread the toggle links and thereby raise the journal box. 105
10. A jack of the class described comprising a pair of toggle links, means for pivotally supporting the upper ends of said links at a fixed point above the journal box, a frame adapted to extend underneath the journal box, another pair of toggle links pivotally connected at their lower ends to the frame, a pair of blocks to which the free ends of both pairs of toggle links are pivotally secured, a rod having right and left hand threaded connections with the respective blocks, and means for rotating said rod to spread the toggle links and thereby raise the journal box. 110
11. A jack of the class described comprising a lever adapted to be fulcrumed intermediate its ends on the rim of a car wheel, means for connecting one end of the lever to the axle, a pair of toggle links pivotally connected at their upper ends to the other end of said lever, a frame adapted to extend underneath the journal box, another pair of toggle links pivotally connected at their lower ends to the frame, a pair of blocks to which the free ends of both pairs of toggle links are pivotally secured, a rod having right and left hand threaded connections with the respective blocks, and means for rotating said rod to spread the toggle links and thereby gradually decrease the distance between the lever and said frame. 115
12. A jack of the class described comprising a lever adapted to be fulcrumed intermediate its ends on the rim of a car wheel, a fulcrum block supporting said lever and on which the lever may be longitudinally adjusted, means for connecting one end of the lever to the axle, means for connecting the other end of the lever to the journal box, one of said connections including toggles, and means for spreading said toggles to decrease the effective length of said connecting means. 120
13. A jack of the class described comprising a lever adapted to be fulcrumed intermediate its ends on the rim of a car wheel, a fulcrum block supporting said lever and on which the lever may be longitudinally adjusted, means for connecting one end of the lever to the axle, means for connecting the other end of the lever to the journal box, one of said connections including toggles, and means for spreading said toggles to decrease the effective length of said connecting means. 125

13. A jack of the class described comprising a lever adapted to be fulcrumed intermediate its ends on the rim of the car wheel, said lever being provided with a flange having a plurality of grooves any one of which is adapted to fit the wheel flange, means for anchoring one end of the lever to the axle, means for connecting the other end of the lever to the journal box, and means for decreasing the effective length of said connecting means to raise the journal box.

14. A jack of the class described comprising a lever adapted to be fulcrumed intermediate its ends on the rim of a car wheel, means for adjusting the fulcrum point of said lever, means for anchoring one end of the lever, means for connecting the other end of the lever to the journal box, and means for decreasing the effective length of

said connecting means to raise the journal box.

15. A jack of the class described comprising a lever adapted to be fulcrumed intermediate its ends on the rim of a car wheel, means connecting one end of the lever to the axle, a frame embracing the journal box, means for connecting the frame to the lever including blocks having right and left hand threads, and links of fixed length connecting the blocks with the frame and lever respectively, a rod having right and left hand threads to engage the blocks, means for rotating the rod in said blocks to thereby raise the journal box.

In testimony, that I claim the foregoing as my own, I have hereto affixed my signature.

JOSEPH JOSEPH GLATT.
